PLEATING MEANS FOR FABRICS
Abe Levine, Brooklyn, N.Y., assignor of one-half to
Gerald L. Berkin, Tokyo, Japan
Filed Nov. 19, 1962, Ser. No. 238,512
2 Claims. (Cl. 160—348)

The invention relates generally to the art of pleating, and more particularly to a drapery or curtain structure.

Uniform distribution of drapery and curtain fullness is controlled either by providing regularly spaced pleats along the width of the drapery or curtain panel or by manually positioning individual hooks or rings along the supporting edges of such drapery or curtain panels for their suspension from curtain or drapery rods. Certain treatments of curtains and draperies provide for fullness distribution and rod suspension by the use of a pleated heading whereby a plurality of uniformly spaced attachment points are created which are in turn connected to the supporting curtain or drapery rod by means of rings or hooks which may be fastened to said attachment points in any of several conventional ways. Such designs are difficult and tedious to make and require particular care in laundering and ironing.

An important object of the present invention is to provide in a simple manner for automatically distributing drapery and curtain pleating fullness heretofore found impossible along a supporting rod and at the same time to create a new and pleasing effect of manipulating the fabric at the heading of drapery and curtain material.

Another important object of the invention is to provide a means by which there also may be provided a simulated pleated heading which is obtainable without the difficulty and labor normally attendant upon the conventional methods of making such headings.

Another object is to provide an improved heading structure for a drapery or curtain panel wherein an enlarged heading hem is provided in the heading edge of the drapery or curtain panel and a pre-folded heading member is provided, the folds being such that the combined curtain and heading member will have the desired pleated appearance, such as that of a cafe curtain, drapery and the like.

Still another object is to provide a heading structure for a drapery or curtain panel, which is easy to fabricate, easy to maintain and launder, and which provides an enlarged body or flare effect in the heading edge of the drapery or curtain panel and permits the use of metal clamping devices which can be quickly and easily removed from the drapery or curtain panel for the purpose of laundering, storing and ironing the fabric.

Another object is to use the unit without any auxiliary hardware, the unit being affixed to the fabric by sewing the fabric to the unit through the respective holes.

Other objects and advantages of the invention are to provide a pleated heading for a drapery or curtain panel or any other fabric which requires no sewing or adhesive, is completely reusable, conceals all hardware, needs no tools, needs no skill, needs no buckram stiffening members, can be used on all kinds of fabrics, is readily removed and attached, provides a better definition of pleats than heretofore available, is not permanently affixed, is completely hidden so that it cannot be soiled, cannot pull apart, stores flat when not in use, is easily ironed and cleaned, is easily packed and shipped, is self-contained and permits easy change of design of pleat, provides a third-dimensional effect to the pleat so that pleat appears to be on outside of fabric, permits a back-tracking of fabric whereby extra fullness in pleat is provided, the back-tracking carrying the pleat down the length of the fabric, provides for the three-dimensional effect, can be used on all existing traverse rods, poles, cafe rods now on the

2

market, wherein all pleats are exactly alike, adaptable for all kinds of fabric panels, adaptable to make a double fold or triple fold using the same unit, can be marketed in the form of a single sheet with several units thereon, 5 can be marketed in long strips and cut as needed at job, or in individual units, the pleats always falling symmetrically whether drape is in an open, closed or in-between position.

For further comprehension of the invention, and of the 10 objects and advantages thereof, reference will be had to the following description and accompanying drawings, and to the appended claims in which the various novel features of the invention are more particularly set forth.

In the accompanying drawings forming a material part 15 of this disclosure:

FIG. 1 is a front elevational view of a heading structure of a drapery panel embodying the invention and shown mounted upon a drapery rod.

FIG. 2 is a rear elevational view thereof.

FIG. 3 is an enlarged fragmentary top plan view of the 20 heading structure, parts being broken away.

FIG. 4 is a vertical sectional view taken on the plane of the line 4—4 of FIG. 2.

FIG. 5 is an enlarged perspective view of a finished 25 pleat, parts being shown broken away.

FIG. 6 is a top plan view of FIG. 5.

FIG. 7 is a sectional view taken on the line 7—7 of 30 FIG. 6.

FIG. 8 is a top plan view of the insert in flatwise condition.

FIG. 9 is a perspective view of the insert of FIG. 8 in partly folded condition.

FIG. 10 is a side elevational view of a fastening element, showing the element in bent operative position.

FIG. 11 is a side elevational view of a pin used with the 35 heading structure.

FIG. 12 is a side elevational view of a supporting hook used with the heading structure.

FIG. 13 is a side elevational view of a modified form 40 of supporting hook used with the heading structure.

FIG. 14 is a view similar to FIG. 6 of a pleat assembly embodying a modified form of the invention.

FIG. 15 is a view similar to FIG. 6 of a pleat assembly embodying another modified form of the invention.

FIG. 16 is a side elevational view of a modified form 45 of pin used with the pleat assembly.

Referring in detail to the drawings, in FIG. 1 a fragment of a drapery heading embodying the present invention is indicated generally by the reference numeral 10 and is shown mounted on a supporting rod 12. The heading 10 comprises a drapery panel 14 which is preferably formed of a fabric material. The panel 14 is shown as provided with a relatively wide hem 16 adjacent to its heading edge 18, which hem provides an elongated flat sleeve or pocket 20, but the hem may be omitted. The hem 16 may be provided in a substantially conventional manner by folding over a portion of the body of the panel material adjacent to an edge thereof and then stitching such portion along the line 22 to the remainder of the panel. The hem 16 may also be left folded without stitching, or may be glued, or a heat sensitive tape may be used. The device will work equally well without a hem.

In accordance with the invention, a series of spaced 65 pleat assemblies 24 are formed at spaced intervals along the heading 10. Each pleat assembly includes a pleat forming strip 30 of relatively stiff material such, for example, as paper or buckram, or metal or plastic. Preferably such strip is made of any desired width. On the strip there is provided a plurality of scored lines 32 which are arranged transversely of said strip and extend from one longitudinal edge to the other longitudinal edge, said

lines 32 designating fold lines along which said strip is to be bent or folded. The fold lines 32 are parallel to each other and may be equally spaced or not as desired, the distances between said fold lines determining the width and spacing of the pleats to be formed. The larger or smaller the spacing of all sides will increase or decrease the fullness of the pleat assembly. All scored lines 32 should fold both ways or only one way, as desired.

It will be understood that the pleat forming strip 30 may be made in various lengths and widths with the fold lines provided thereon at any desired predetermined equal or unequal spacing to form pleat assemblies of any desired size and number. Thus in the form of strip shown in FIG. 8, the fold lines 32 are arranged to form a predetermined number of pleat assemblies with said assemblies spaced apart a predetermined distance. In the form of strip 30 shown in FIG. 8, the fold lines 32 are equally spaced apart throughout the entire length of said strip. However, the fold lines do not have to be equally spaced. The strip 30 may be made in strip form or of great length to be wound on a spool or reel whereby portions of any desired length may be cut therefrom, or in individual units.

Referring to FIG. 9, it will be seen that by simply folding or bending the strip 30 at the fold lines 32 there will immediately be formed a group of pleats 33 comprising the faces 40, 42, 44, 46, 48, 50 adapted to be brought into contact with each other. The faces of the strip formed by the fold lines, except the outer faces 40 and 50, are formed with a top row of aligned holes 52 and with a bottom row of aligned holes 54. In view of the stiffness of the strip 30, the location of the fold lines 32 are readily ascertainable, the strip folding naturally and with ease and automatically at said fold lines.

In use, the strip 30, which has both sides roughened similar to sandpaper so that when the fabric comes into contact with the unit it does not slide and is more controllable, is placed flatwise on the inner surface of the fabric to be pleated. Thus, for example, where it is desired to provide pleat assemblies such as the pleat assemblies 24 of FIG. 1, the strip 30 is attached to the inside of the fabric comprising the drapery panel 14 at that portion thereof where it is desired to form the pleats. The strip 30 then functions as a guide in forming the pleats as by bending the strip along its fold lines. The fabric of the panel 14 will be folded by squeezing the folds together and the fabric will be clamped to the unit by insertion of the legs 56 of a U-shaped brad or pin 58 through the holes 52 and 54 in the intermediate faces and through the fabric of the panel and then bending over the legs 56 of the brad or pin. The intermediate faces 42, 44, 46, 48 with fabric are thus secured to each other in partly folded condition.

The outer faces 40 and 50 of the strip with fabric between them are then folded inwardly against the adjacent faces 42 and 48, respectively, forming outer folds or loops 60, 60. This inward folding of the fabric causes the pleats to fall straight down the entire length of the fabric and to cause the three-dimensional effect. In addition, the inward or backtracking of the fabric conceals the U-shaped brad or pin 58. The legs 62, 62 of an elongated bobby pin 64 are then inserted between or into the loops 60, 60 adjacent the panel, thereby pulling the faces 40 and 50 with the fabric into engagement with the faces 42 and 48, respectively, and holding said faces with fabric in engagement. The faces of the pleats with fabric are thus held in intimate contact with each other to form an assembly of three pleats as indicated at 24 in FIG. 1.

Hook devices 68 shown in detail in FIG. 12 are removably secured to the fabric of the panel adjacent the pleat assemblies 24 in the rear of the drape, in a vertically disposed arrangement, the pin-pointed base 70 of the hook being inserted into the fabric with the hook

portion 72 opening downwardly. Hooks 68, substantially S-shaped, with one end bifurcated forming prongs 70, shown in FIG. 13, may also be used and inserted into the fabric. The drapery panel 10 is now ready to be mounted upon a supporting drapery rod, such as the rod 12.

The strip 30 therefore serves not only to provide predetermined bends and folds in the fabric of the drapery panel 10, but also to strengthen that portion of the drapery panel 10 adjacent to the heading of said panel.

When it is desired to launder the drapery panel 10, the hook devices 68 are first removed from the panel after which the bobby type pins 64 are removed by merely withdrawing them from the outer loops 60, 60. Next the U-shaped brad or pin 58 is removed. The pleats 24 can then be unfolded and the strip 30 readily removed.

In FIG. 14, a modified form of pleat assembly 24' is shown. In this form, only two pleats 24' are formed as distinguished from three pleats as shown in FIGS. 1 and 6. In all other respects the pleat assembly is similar to the pleat assembly 24 and similar reference numerals are used to indicate similar parts.

FIG. 15 illustrates a further modified form of pleat assembly 24" wherein the strip 30" is folded only once to provide a single pleat in the fabric of the panel 14. The folds in the strip and fabric are held together by headed pins 66, preset in the unit in conjunction with a bobby type pin, such as pin 64. A cotter pin 76 as shown in FIG. 16 may also be used.

It will be understood that the invention contemplates that one individual pleat can be attached to the fabric while the drape is on the rod at the window, if necessary. Furthermore, a thicker or thinner unit will affect the fullness of the pleat. It is also understood that a unit may be formed on the bottom of the fabric in order to weigh the pleat down.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. In a drapery pleat construction, a drape, a rectangular form of relatively stiff foldable material applied to a portion of the rear surface of said drape at the upper end thereof, said form having a plurality of spaced parallel vertically disposed pre-scored fold lines defining a pair of end panels and a pair of intermediate panels, apertures in said panels, said panels and the said drape section applied thereto being folded accordion fashion along said fold lines, said end panels and the intermediate panels connected thereto providing a pair of rearwardly facing re-entrant end angles and the connected intermediate panels providing an intermediate forwardly facing connecting reentrant angle, the section of said drape at each end of said form being folded back and forth upon itself into and back out of the adjacent reentrant end angle to form a pair of inner loops within said reentrant end angles and a pair of outer loops at the free ends of said end panels, horizontally disposed securing means extending from inner loop to inner loop through said panel apertures for maintaining said drape in folded condition, and a vertically disposed U-shaped spring clip having the legs thereof extending downwardly into said outer loops for maintaining the looped sections of said drape at each end of said form in firm contact with each other.

2. The method of forming a drapery pleat comprising; applying a rectangular form of relatively stiff foldable material having a plurality of spaced parallel vertically disposed pre-scored fold lines defining a pair of end panels and a pair of intermediate panels to a portion of the rear surface of a drape at the upper end thereof; folding

said form and the drapery portion applied thereto along said fold lines accordion fashion to provide a pair of rearwardly facing reentrant end angles and a forwardly facing connecting intermediate reentrant angle; folding the portions of said drape at each end of said form back and forth upon itself into and out of the adjacent reentrant end angle to provide a pair of inner loops within said reentrant end angles and a pair of outer loops at the free ends of said end panels; inserting a securing means from inner loop to inner loop horizontally through aligned apertures in said intermediate panels to thereby maintain said drape and form in folded condition; and then inserting the legs of a U-shaped spring clip downwardly into said outer loops to thereby maintain the outer looped portions of said drape in firm contact with each other.
